AEROPLANE.

1,324,393.

Specification of Letters Patent.

Patented Dec. 9, 1919.

Application filed September 21, 1918. Serial No. 255,144.

To all whom it may concern:

Be it known that I, CLINTON GRAY, a citizen of the United States, residing at Atlantic City, in the county of Atlantic and State of New Jersey, have invented certain new and useful Improvements in Aeroplanes, of which the following is a specification.

This invention relates to aeroplanes and one of the primary objects of the present invention is to provide in an aeroplane, a novel construction and arrangement of propellers.

Another object of the invention is to provide propeller mechanism which will adapt the aeroplane to be driven substantially directly upwardly at the beginning of a flight, thus avoiding necessity of the usual running start and permitting an aeroplane equipped with the propeller mechanism to be employed upon battle-ships and under other conditions where economy in landing and starting space is necessary.

Another object of the invention is to so arrange the propellers that the aeroplane will be sustained thereby and by the sustaining planes of the aeroplane in a pendulum-like manner, thus obviating accidental tipping of the plane in flight.

In the accompanying drawings:

Figure 1 is a side elevation of the aeroplane embodying the improvements of the present invention;

Fig. 2 is a top plan view of the aeroplane;

Fig. 3 is a vertical transverse sectional view through the forward portion of the aeroplane;

Fig. 4 is a perspective view of one of the propeller blades;

Fig. 5 is a perspective view of one of the propeller hoods;

Fig. 6 is a view in elevation of the means provided for adjusting the propeller hood.

As the present invention may be employed upon aeroplanes of various types without departing from the spirit of the invention, the aeroplane is illustrated in a conventional manner as having a frame indicated in general by the numeral 1 and of any desired construction although it preferably includes landing runners 2, parallel upper fore and aft bars 3, and side uprights or vertical bars

4 just below and spaced slightly from the fore and aft bars 3. 55

The propeller shaft is indicated in the drawings by the numeral 6 and this shaft is mounted rotatably in suitable bearings 7 upon the frame members 3 and has fixed to its intermediate portion a sprocket gear 8 over which is passed a sprocket chain 9 passing also over a sprocket gear 10 upon the shaft 11 of an engine indicated in general by the numeral 12 and of any suitable type, the shaft 6 being preferably located just above the planes 5 and between the front and rear ends of the top of the frame of the aeroplane, and the engine being located at the bottom of the frame and in advance of the said shaft. 60

In the illustrated arrangement, there are two of the propellers mounted within an opening or recess 5' in the front edge of the uppermost plane, the major portion of their bodies standing well above such plane; and in the structure embodying the present invention each of these propellers comprises a series of propeller blades of the construction shown in Fig. 4 of the drawings. The propeller blade illustrated in Fig. 4 is indicated in general by the numeral 13 and includes side members 14 which extend parallel to each other and at their inner ends are provided with collars 85 15 which are secured in any suitable manner to the shaft 6 or to a hub common to all of the blades of each propeller. At their outer ends the side members 14 are connected by a cross member 16, and intermediate their ends by a cross member 17 extending parallel to the member 16. Near their inner ends the side members 14 are further connected by a cross member 18. A plane surface 19 is stretched between the side members 14 and the cross members 17 and 18, as shown in Fig. 5. A cupped surface indicated by the numeral 20 having the general form of a section of a cylinder occupies the space defined by the frame members 14, 16 and 17, 100

this surface being of cloth, suitably treated, aluminum, or any other material found suitable for the purpose and where the material is cloth the same will be braced or stretched over a suitable frame to give it the proper form. Of course, the concave sides of the outer ends of the propeller blades are all presented in the same direction and in the direction of rotation of the shaft 6 and the 5 blades comprising each propeller set are equidistantly spaced about the said shaft and are radial thereto. Due to the peculiar cupped formation given the outer ends of the propeller blades, these blades will 10 possess maximum lifting and propelling power as, in their rotation, air will be trapped in their cupped outer portions. Of course, in the absence of any means to prevent, the propellers would act equally in all directions 15 against the air, but the present invention contemplates the provision, in connection with each propeller, of a hood and means for adjusting the hood so that substantially only one-half of each propeller is 20 substantially only one-half of each propeller is 25 at any time effective.

One of the hoods is shown in Fig. 5 and is indicated in general by the numeral 21 and comprises side walls 22, an open front 23, and an arcuate substantially semi-cylindrical wall 24 which extends between the 30 arcuate outer edges of the side walls 22. The side walls 22 at their chordal edges or sides are provided with suitable bearing collars 25, which are loosely fitted to the 35 shaft 6 thus adapting the respective hood to be swung about the shaft as an axis. By reference to Fig. 1 of the drawings it will be observed that the hoods, being substantially semi-cylindrical inclose substantially 40 one-half of the respective propeller, the propeller rotating within the hood and the hood being adjustable within the opening or recess 5'.

In order that the hoods 21 may be adjusted as heretofore stated, a shaft 26 is mounted in suitable bearings 27 upon the runners 2 of the frame of the machine and this shaft has fixed to it rearwardly extending crank arms 28 to which are connected the 50 lower ends of rods 29, which rods at their upper ends are pivotally connected to the adjacent sides 22 of the hoods 21. Of course, when the shaft 26 is oscillated, the hoods will be swung about the shaft 6 as 55 a center, and in order that the shaft may be so oscillated, means is provided which will now be described. Within the frame of the machine there are mounted two operator seats 30 each respectively located beneath one of the said hoods 21 and consequently at opposite sides of the middle of the machine as a whole. Operating levers 31 are fixed to the shaft 26 near the ends thereof and each located adjacent the 60 respective seat 30 and at one side of the said

seat, the shaft 26 being adapted to be oscillated through backward or forward rocking of either of the said levers 31. To hold the shaft in positions of adjustment a pawl device is provided which includes rock arms 70 32 each having at its inner end a flat tooth 33, the lower edge of which is designed to engage in the teeth of a segmental rack 34, the rock arms 32 being pivotally mounted near their tooth carrying ends upon suitable brackets 35 fixed upon the shaft 26. Springs 36 bear between the shaft 26 and the arms 32 at that side of the pivots for the arms opposite the sides at which the tooth carrying ends of the arms are located, 75 and these springs normally hold the teeth 33 of the two arms in engagement with the segmental rack. A pin and slot connection 37 between the teeth 33 of the two arms serves to prevent relative separation of the 80 teeth and yet permits of movement of the teeth into and out of engagement with the segmental rack when the arms 32 are rocked upon their pivots 35. The outer end of each arm 32 extends beside the respective hand 85 operating lever 31 and a rod 38 is pivotally connected at its lower end as at 39 to the outer end of the respective arm 32 and at its upper end to one end of an angular pawl lever 40 pivotally mounted upon the respective operating lever 31 as at 41 and having a hand grip as is usual, indicated by the 90 numeral 42, extending beside the handle of the said lever 31. It will now be understood that when the occupant of either seat 30 sees 100 the necessity for adjusting the hood 21, he may do so without the co-operation of the occupant of the other seat 30 by grasping the handle of his operating lever 31 and the hand grip 42 associated with the same and 105 so rocking the pawl lever 40 upon its pivot as to depress the outer end of the respective arm 32 against the tension of the spring 36. Thus the tooth carrying end 33 of this rod will be swung upwardly, and through the 110 pin and slot connection 37 between the two teeth 33, the other arm 32 will be correspondingly rocked and both teeth will be disengaged from the segmental rack 34, thus permitting the shaft 26 to be rocked through 115 the medium of the selected lever 31. When the hoods are positioned with their chordal edges substantially vertically and the propellers are in motion, the propellers will 120 exert a direct upward lifting force and the machine may be driven substantially directly vertically into the air from a standing position. After the machine has reached the desired elevation, the hoods may be adjusted so as to position their said edges in a more 125 or less horizontal plane and downwardly presented so that then the lower sides of the propeller will be the effective sides and the machine will be driven in a forward direction, the sustaining planes at such time act- 130

ing to sustain the machine in its flight. Of course, the hoods may be adjusted to assume various intermediate positions.

Whatever the adjustment of each hood 5 around its propeller, the exposed portion of the propeller acts on the air and has its effect upon the aeroplane, while that portion of the propeller which moves within the hood finds little resistance because of the 10 peculiar shape of the blade. The cupped outer portion 20 of the blade which trapped air on the working side of the propeller, carries it around into and through the hood practically without loss, whereas the plane 15 surface 19 when it moves into the hood co-acts with the curved wall and the ends thereof so that all the air on this side of the propeller is caused to pass through the hood.

Also, air drawn into the lower side of the 20 hood by the surfaces 19 and 20 of each blade will be carried around by such blade, moving outward meanwhile under centrifugal force, and finally driven upward against the upper part of the hood just before the 25 blade comes out at the top; and to a certain extent this air will assist in raising the aeroplane.

The rudder mechanism includes front and rear rudders indicated in general by the 30 numeral 43 and each comprising canvas or sheet metal 44 stretched over spreader frames 45, which frames are fixed to and carried by vertically mounted oscillatory uprights 46 located one at the front and the 35 other at the rear of the machine. The uprights 46 are provided at their upper and lower ends with cross arms 47 and connecting the ends of the respective cross arms of the uprights 46 at the front and rear of the 40 machine, are crossed cables 48 which provide for simultaneous oscillation of the uprights when either upright is turned toward the right or toward the left. To provide for this oscillation of the uprights to angularly 45 adjust the propellers 43, steering shafts 49 are mounted within the frame of the machine one in front of each seat and carry at their upper ends steering wheels 50 by which they may be turned, the lower ends 50 of the shafts carrying cross arms 51 to which are connected cables 52 also connected to the lower cross bar of the forward rudder 43.

In addition to the rudders 43, the machine 55 embodies a tail rudder indicated in general by the numeral 53 and preferably transversely arched, the concave side of this rudder presented downwardly and the rudder being pivotally connected at its forward side 60 as at 54 with the rear end of the frame of the machine in a manner to permit of its transverse swinging adjustment. In order to brace and guide the rudder in its swinging adjustment, a cable or other flexible connection 65 55 is connected at its ends as at 56 with

the forward corners of the rudder, and at its intermediate portion is passed about pulleys 57 mounted at suitable points at the rear end of the frame of the machine. For the purpose of swinging the rudder 53, cables 58 are 70 connected at their rear ends to the rudder near the rear corners thereof, as indicated by the numeral 59 and at their forward ends are connected to the upper cross bar 47 for the rear rudder 43.

Having thus described the invention, what is claimed as new is:

1. In an air craft, a power driven shaft, a propeller thereon, a hood adjustable on the shaft and partly inclosing the propeller, a 80 rock shaft having a crank arm connected with said hood, and spaced operating levers on said rock shaft; combined with a toothed rack adjacent the rock shaft, two rock arms pivoted to this shaft and having teeth at 85 their inner ends lapping each other over said rack, pin-and-slot connections between said teeth, and hand grip mechanism carried by said operating levers and connected with the outer ends of said rock arms.

2. In an aeroplane, a rotary shaft, propellers carried by the shaft, means for rotating the shaft, hoods angularly adjustably mounted about the shaft and partly inclosing the respective propellers, a rock shaft, 95 operative connection between the rock shaft and the hoods for rotatably adjusting the hoods when the shaft is rocked, spaced operating levers fixed upon the shaft, a segmental rack between the levers, arms mounted for rocking movement upon the shaft, a pawl lever upon each of the operating levers, connection between each pawl lever and the respective arm, and teeth carried by the adjacent ends of the arms and pivotally connected and simultaneously engageable with the segmental rack.

3. In an aeroplane, a supporting frame including upper and lower spaced fore and aft bars connected by vertical bars, a sustaining plane secured to the vertical bars in spaced relation to and below said upper bars, a propeller shaft extending between said upper bars, a propeller hood journaled on the shaft between the upper bars, and means for adjusting the hood, the forward edge of the plane being cut away to receive the propeller and hood.

4. In an aeroplane, the combination with a plane having a recess opening through the 120 front edge thereof, a shaft crossing the recess, and a propeller carried by the shaft and standing within said recess with its major portion above the plane, whereby the forward thrust of the working side of the 125 propeller is substantially in line with the plane; of a hood partly inclosing the propeller and also standing within said recess, and means for adjusting the position of the hood.

5. In an aeroplane, a shaft, means for driving it, a propeller fast on the shaft and each blade including radial members connected near the shaft by a plane surface and remote therefrom by a surface of semi-cylindrical cross section closed at its ends, a substantially semi-cylindrical hood partly in-
- closing the propeller and mounted for adjustment on the shaft, and means for setting the hood to expose a selected portion of the propeller.
- In testimony whereof I affix my signature.

CLINTON GRAY. [L.s.]
